UNITED STATES PATENT OFFICE.

SOLON OSMOND RICHARDSON, JR., OF TOLEDO, OHIO.

MANUFACTURE OF GLASS.

SPECIFICATION forming part of Letters Patent No. 764,501, dated July 5, 1904.

Application filed March 28, 1903. Serial No. 150,007. (No specimens.)

To all whom it may concern:

Be it known that I, SOLON OSMOND RICHARDSON, Jr., a citizen of the United States, residing at Toledo, in the county of Lucas and State of Ohio, have invented certain new and useful Improvements in the Manufacture of Glass, of which the following is a specification.

The object of my invention is to provide a process for effectively casting glass directly from the working chamber of a glass-furnace without intermediate handling, and especially to provide such a process in connection with a continuously-operating glass-furnace. These and such other objects as may hereinafter appear are attained by the process hereinafter described, which may be conveniently practiced with the apparatus shown in the accompanying drawings, in which—

Figure 1 is a plan view of one form of furnace embodying my invention, the view showing part of the crown broken away. Fig. 2 is a longitudinal sectional view thereof on the line 2 2 of Fig. 1. Fig. 3 is a vertical sectional view on the line 3 3 of Figs. 1 and 2 looking in the direction indicated by the arrows. Fig. 4 is a transverse section on the line 4 4 of Figs. 1 and 2 looking in the direction indicated by the arrows. Fig. 5 is a perspective view showing part of the crown and walls of the furnace broken away. Fig. 6 is a vertical sectional detail on the line 6 6 of a modification of my invention, and Fig. 7 is a plan view of Fig. 6 with part of the crown and walls broken away.

Like letters of reference indicate the same parts in the several figures of the drawings.

Referring by letter to the accompanying drawings, A indicates the outer walls of a familiar form of tank-furnace, said furnace being divided by a bridge-wall B into a reducing-chamber C and a working chamber D, connected by a passage E through said bridge-wall. The bridge-wall B does not extend to the top of the furnace.

F F indicate regenerators of any familiar type having air and gas ports and by means of which the batch is reduced.

F' is the crown of the furnace, extending

over the reducing-chamber C and the working chamber D.

The bridge-wall being of less height than the furnace, it will be obvious that there is free communication between the chambers C and D over the top of the bridge-wall. The end wall G of the furnace is also of less height than the furnace and may be, as shown, of substantially the same height as the bridge-wall and provided with a spout H.

Arranged adjacent to the wall G of the furnace is an auxiliary structure I, comprising a casting-chamber J and an adjoining chamber K. The spout H projects into the casting-chamber J, as is clearly shown in Fig. 5. The casting-chamber J is separated from the adjoining chamber K by means of an arch L, opposite to which is a second arch M, so arranged that a table N, with whatever is carried thereby, may pass thereunder. (See Fig. 3.) As illustrated in the drawings, the table N is mounted on trucks O, arranged to run on rails P. Adjacent to the table N and preferably connected therewith in any convenient manner is a blank or block Q, arranged to be moved along the rails P and of such dimensions that when moved into the casting-chamber J it will substantially fill all of the space between the vertical walls of said chamber below the arches, thereby shutting off communication between the interior and the exterior of the furnace.

As shown in Fig. 1 the parts are arranged for use in the manufacture of plate-glass. The furnace being of the continuous type, the metal as it fills the working chamber D will overflow through the spout H and onto the table N. The casting-chamber being in free communication over the walls G and B with the interior of the furnace, a fierce heat will be radiated into the casting-chamber and above the table N and of a sufficiently high temperature to maintain the glass in a liquid condition while the plate of glass is being cast upon the table N. As soon as the working chamber D is filled the metal will overflow through the spout H and onto the table N. The casting-chamber being in direct and free commu-

nication with the reducing and working chambers, the temperature in the casting-chamber may be maintained at such a degree that the metal as it flows through the spout H and onto 5 the table N is at substantially the same temperature, and consequently at the same degree of fluidity, as in the working chamber D, and so I obtain an even flow and spread of the glass upon the table N before there is any 10 such cooling and solidifying of the glass as will interfere with the casting process. As the glass flows from the spout H in a fluid stream, it is only necessary to close the spout H in any well-known manner to stop the flow 15 of glass, so there will be no instrumental cutting of the glass and no resulting shear and consequent marring of the casting.

In Figs. 6 and 7 I have shown a modified form of my furnace in which I use a cylindrical ladle U, pivotally mounted below the spout H and provided with a casting-spout u, the top of the ladle immediately adjacent to the spout H being open. In connection with this modification I can conveniently use a pivoted casting-table V, extending partially outside of one wall of the casting-chamber and arranged to support a number of molds W. The cylindrical ladle U may be conveniently operated by a crank-arm X, extending outside of the furnace and arranged to move the ladle upon its pivot. In using this modified form of my invention the ladle U is normally in the position shown in dotted lines in Fig. 7. The table V is rotated upon its pivot, the 35 molds W being placed in order upon the exposed portion of the top of the table, which projects outside of the furnace, and being brought in turn under the spout u of the ladle U. By means of any convenient peephole the position of the molds can be watched, and as each mold in turn comes under the ladle U the ladle will be tipped to casting position, as shown in Fig. 7, and will be returned to the position shown in dotted lines 40 in Fig. 6 as each casting is completed. The continued rotation of the table V in turn brings each filled mold outside of the furnace, where it can be removed and replaced by an empty mold, and so the casting process can 45 be carried on continuously.

When using my process with an apparatus constructed as shown in Figs. 6 and 7, I have the advantage of being able, by means of my process, to fill each mold in its turn with perfectly fluid glass, which flows freely into the 55 molds, fills every corner and interstice with-

out the necessity for pressure of any sort, and which settles to an even level and leaves a smooth and finished top surface.

While for motives of economy it is desirable to heat the casting-chamber in the manner shown in the drawings by heat radiated from the reducing or working chambers, or both, obviously the desired temperature can be maintained in the casting-chamber by auxiliary or entirely independent means without departing from the spirit of my invention. For the purposes of my process it is only necessary that the temperature in the casting-chamber shall be such a temperature as shall 60 maintain the fluidity of the glass during its casting. In practice there may be without harm a variation of several hundred degrees in temperature, for, as is well known in this art, there is often such a variation in the temperature of the glass at different points in the melting-pot while the glass is all in a molten state.

I claim—

1. The process of manufacturing glass, which 80 comprises confining a body of molten glass in the presence of a reducing temperature, continuously adding fresh batch to the molten glass so confined, thereby causing a portion of the molten glass to overflow into a casting 85 zone in which the temperature is kept at a sufficient degree to maintain the glass in a sufficiently fluid condition to permit of its being cast into definite form, and conducting such overflow into means located in said casting zone, whereby the glass so conducted is given definite form.

2. The continuous process of manufacturing glass, which comprises subjecting a body of molten glass to a continuously-maintained 95 reducing temperature, adding fresh batch to said body of molten glass, thereby causing a portion of the molten glass to overflow into a casting zone, maintaining the temperature in said casting zone, by heat radiated from the reducing zone, at a degree sufficiently high to maintain the overflowing glass in a sufficiently fluid condition, and casting the glass into definite form within said casting zone by conducting such overflowing glass 100 into suitable casting means located within said casting zone.

SOLON OSMOND RICHARDSON, JR.
